Fig. 3

Fig. 1 is a perspective view of the foldable step ladder; Fig. 2 is a front elevation of the same on a somewhat reduced scale; and

Fig. 3 is a side elevation on the same scale as Fig. 2. The design incorporates the novel characteristic of a bowed loop integral with and connecting the front legs or stiles of the ladder, said loop extending well above and beyond the center of the locking platform, and the loop being of such size that it overhangs or extends beyond the upper portion of the sides of the ladder, all as shown.

I claim:
